UNITED STATES PATENT OFFICE.

THEODORE GRISSINGER, OF MECHANICSBURG, PENNSYLVANIA.

FLY-NET.

SPECIFICATION forming part of Letters Patent No. 243,701, dated July 5, 1881.

Application filed December 7, 1880. (No model.)

To all whom it may concern:

Be it known that I, THEODORE GRISSINGER, a citizen of the United States, residing at Mechanicsburg, in the county of Cumberland and State of Pennsylvania, have invented certain new and useful Improvements in Fly-Nets; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 The object of the present invention is to furnish a fly-net for horses which shall be cheaper and more durable and attractive than other nets heretofore known or used.

20 The invention consists in making the longitudinal ribs and pendent lashes which constitute a fly-net of india-rubber, as will be herein-after more fully described.

25 The accompanying drawing shows a fly-net which has the ribs and lashes made with a core of cord covered with india-rubber.

The longitudinal ribs A and pendent lashes B, comprising the net, are made of strips or cords of india-rubber of any desired form and size. The lashes are secured to the ribs by 30 means of adhesive cement, or by any of the well-known methods of joining pieces of india-rubber. The ribs may be divided longitudinally, or be made of two strips with the lashes secured between them. The customary way 35 for securing leather lashes to ribs of the same material may also be resorted to. For example, the lashes may be run through openings in the ribs.

The shape, size, or configuration of a fly-net 40 made of india-rubber, as proposed by me, depends upon circumstances or the taste or requirements of the dealer or purchaser.

The advantages which an india-rubber fly-net possesses over one made of leather may be 45 briefly stated as follows, viz: As india-rubber is impervious to water or moisture, nets made of this material are not injuriously affected by

becoming wet or by the sweat of a horse. For the same reason an india-rubber net can be washed or cleaned, when dirty, without injury thereto. Fly-nets made of leather are objectionable for various reasons, and their use is attended with many disadvantages. For example, a frequent oiling of the leather nets is necessary to preserve the pliability of the leather, 55 and when they get wet they warp or twist out of shape. Moreover, a leather net requires a lash-fastening medium, which generally necessitates the formation of a knot, thus detracting from the finish or appearance of the net. Animals and vermin frequently destroy or injure leather nets; but india-rubber nets are safe from their attacks. Leather nets, for obvious reasons, are generally made black, whereas an india-rubber net can be made of different colors, 60 so as to present a more ornamental appearance.

I have described my invention as consisting, broadly, in the use of india-rubber for fly-nets, the india-rubber being formed into strips or 70 cords by suitable means, so as to form ribs and lashes. I also contemplate making the ribs and lashes of an inner core of cord, twine, or tape and an outer covering of india-rubber, thus securing greater strength and durability 75 than when made of rubber alone.

A fly-net made entirely of india-rubber possesses the property of adapting itself to the movements of the horse. This is desirable in order to avoid the disarrangement of the net 80 when in use.

Having thus described my invention, what I claim as new, and desire to secure by Letters Patent, is—

A fly-net for horses having its ribs and 85 lashes made of india-rubber, as herein set forth.

In testimony whereof I affix my signature in presence of two witnesses.

THEODORE GRISSINGER.
